UNITED STATES PATENT OFFICE

JAMES GERALD AMES, OF AURORA, ILLINOIS

COMBINATION GAS FIXTURE

Application filed July 5, 1929. Serial No. 375,919.

This invention relates to an improved combination gas fixture of compact and neat form adapted to occupy a small amount of floor space and arranged to afford a culinary fixture combining a plurality of gas burning appliances including a refrigerator, water heaters, a stove, and an incinerator associated with one another to use a common flue permitting the various appliances to be properly vented and furthermore permitting the waste heat escaping through the flue to be utilized for the purpose of heating the water in an auxiliary water heater affording a hot water supply adapted to be withdrawn from the auxiliary water heater or permitting the same to be admitted into the main hot water heater as a preheated water supply.

It is an object of this invention to provide an improved combination gas fixture including a waste heat water heater, a range, a refrigerator, a main water heater and an incinerator so designed and arranged that in their operation the escaping heat in the flue gases of the various appliances are utilized to heat the water contained in the waste heat water heater.

It is also an object of this invention to provide an improved combination gas fixture wherein a plurality of gas using appliances are closely associated one with the other permitting the recovery of heat from burned gases to be utilized to preheat water in an auxiliary heater before said water is admitted into a main water heater tank thereby permitting a main water heater of smaller capacity to be used to not only conserve space but furthermore afford an arrangement adapted to reduce the amount of gas necessary for hot water heating.

It is a further object of this invention to provide an improved combination gas fixture wherein a gas refrigerator is arranged above a hot water heater so that the water used for the refrigerator cooling system is first led as cold water through the coils around the absorber and condenser of the refrigerator prior to being admitted into the water heater tank to permit heat to be absorbed from the cooling water permitting the amount of cool-

ing water for use by the refrigerator to be materially reduced.

It is furthermore an object of this invention to provide a combination gas fixture wherein a plurality of gas heated and controlled appliances are associated in a compact unit and embrace a waste heat water heater mounted in the hood of the gas range with said hood provided with a cover which is adjustably mounted to not only afford a concealment of the waste heat water heater but to additionally serve as an adjustable means adapted to be extended over the cooking top of the range to carry off gases and odors.

Another object of the invention is to provide a combination gas fixture comprising a plurality of gas controlled appliances including a gas range and an incinerator having a drawer slide removably mounted therebelow and carrying both a broiler and an ash pan for the incinerator.

Another object of the invention is to provide a combination gas fixture comprising a plurality of gas controlled appliances including a gas range having an incinerator mounted in the rear thereof and embracing a foot pedal controlled incinerator door positioned in the rear portion of the top of the gas range having a connection with grates which are adjustably mounted within an incinerator basket or housing and adapted to be operated with the opening of the incinerator door to cause a shaking action to be applied to the grates to cause the removal of ashes from the incinerator basket each time the incinerator cover is opened.

It is an important object of this invention to provide an improved combination gas fixture embracing a unit wherein a plurality of gas controlled appliances are assembled in coacting relation to use a common flue from which the escaping heat from the various appliances is utilized for the purpose of heating water in an auxiliary heater for preheating the water admitted into a main hot water heater, said auxiliary heater being mounted in a hood positioned above a gas range and an incinerator, said unit having a common lighter adapted to light any one or all of the 100

cooking burners, the oven burners or the incinerator burner.

Other and further important objects of this invention will be apparent from the disclosures in the specification and the accompanying drawings.

This invention (in a preferred form) is illustrated in the drawings and hereinafter more fully described.

10 On the drawings:

Figure 1 is a front elevation of an improved combination gas fixture embodying the principles of this invention.

Figure 2 is a side elevation of the fixture.

15 Figure 3 is an enlarged vertical sectional view taken on line III—III of Figure 2 with parts shown in elevation.

Figure 4 is a vertical sectional view of the fixture taken on line IV—IV of Figure 3.

20 Figure 5 is another vertical view of the fixture taken on line V—V of Figure 3 with parts shown in elevation.

Figure 6 is an enlarged vertical detail view of the incinerator taken on line VI—VI

25 of Figure 5.

Figure 7 is a horizontal sectional view of the fixture taken on line VII—VII of Figure 3.

Figure 8 is a fragmentary vertical section 30 through the incinerator appliance taken on line VIII—VIII of Figure 7 and illustrating the operation of the incinerator cover in dotted lines.

Figure 9 is a fragmentary detail sectional 35 view of the incinerator cover operating mechanism taken on line IX—IX of Figure 3.

As shown on the drawings:

The improved combination gas fixture of this invention is of unitary construction to 40 form a single article of furniture embracing a plurality of gas fired appliances arranged in compact relation within a box or cabinet 1 supported on legs 2 and having a common outlet flue 3 projecting from the 45 top thereof for the escape of flue gases, odors and the like. The upper section of the flue 3 projects downwardly through the top of the fixture cover in the form of an elbow 4. The inner end of the flue elbow 4 terminates in 50 an outlet chamber 5 provided in a drum head 6 mounted in one end of a waste heat water container or cylinder 7 disposed within an insulating casing or housing 8. The drum head 6 is also provided with a lower 55 intake chamber 9. Mounted in the opposite end of the waste heat container or cylinder 7 is a drum head 10 having a connecting chamber 11 therein as clearly illustrated in Figure 3. Mounted within the lower half 60 of the waste heat cylinder 7 are a plurality of auxiliary flue pipes 12 which connect the drum head outlet chamber 9 with the drum head chamber 11. Also mounted within the waste heat water cylinder 7 are a plurality 65 of auxiliary flue pipes 13 which connect the

drum head chamber 11 with the outlet chamber 5 of the drum head 6. The waste heat water heater is mounted in the upper portion of the fixture beneath a hood 14. The front of the hood 14 is normally closed by 70 means of a pivotally supported apron or shield 15 which in its normal vertical position serves to hide the waste heat water heater from view. The apron 15 is adapted to be pulled outwardly into an inclined or 75 horizontal position to extend or increase the size of the hood to cover a larger portion of the gas range mounted therebelow. Projecting into the lower portion at one end of the waste heat cylinder 7 is a water supply 80 pipe 16 which is connected with a branch pipe 16a, connected with a water supply pipe 42. Also mounted within the waste heat water heater cylinder 7 is a hot water outlet pipe 17 which extends downwardly 85 out of the cylinder 7 and is conducted downwardly to connect with a supply pipe 18 leading into a cylinder 19 of a main hot water appliance mounted in the lower rear portion of the casing or cabinet 1.

90 The hot water tank 19 is enclosed within an insulation housing or jacket 20. Projecting upwardly into the water tank 19 is a burner hood or pipe 21 the lower outer end of which is open and is positioned directly 95 above a gas burner 22 connected with a gas supply pipe 23. The auxiliary gas pipe 23 leads to a gas controlled thermostat 24 which projects into the hot water tank 19 as clearly illustrated in Figure 3. The thermostat 24 is connected to a gas supply pipe 25. Connected with the burner hood 21 is a pipe 26 which connects up with a chambered drum head 27 provided in one end of the water tank 19. Also connected with the chambered 100 drum head 27 are a plurality of pipes 28 which project through the lower portion of the water tank 19 and connect up with a chambered drum head 29 disposed in the opposite end of the water tank 19. A hot water outlet pipe 30 leads downwardly out of the hot water supply tank 19.

105 The hot water heating unit mounted in the lower rear portion of the fixture cabinet occupies only a portion of the space in that section of the cabinet affording a utensil compartment in front of and below the hot water tank 19. The utensil compartment may be separated from the rear portion of the compartment in which the hot water heater is mounted by a partition of any suitable design. The utensil compartment is accessible 115 through a lower front door 31 on the inner face of which a utensil supporting rack or shelving 32 is supported. The partitions or walls forming the utensil compartment in the lower front portion of the cabinet form a removable unit which may be removed when necessary to gain access to the hot water heat- 120

er and the pipe system mounted in the lower rear portion of the cabinet.

Located adjacent the hood 14 and above the hot water unit and the utensil compartment is a gas controlled refrigerator comprising a 5 refrigerator box 33 enclosed by an insulating jacket or outer housing 34. The refrigerator box is accessible through a front door opening adapted to be closed by means of a refrigerator door 35 having a filling of heat 10 insulating material as illustrated in Figure 7. A plurality of removable shelves 36 are mounted within the refrigerator box 33 below a refrigerator unit 37.

15 Mounted in the flue chamber which is located between the refrigerator and the waste heat water unit in the hood 14 is a refrigerator unit condenser coil 38 and an absorber unit 39 which are connected together and which are also connected with the refrigerator unit 37 by a suitable piping and the like. Also mounted in the flue chamber 40 is a gas 20 thermostat 41 which is connected with the gas supply pipe 25 and is adapted to govern the gas consumption required for the proper 25 operation of the refrigerator unit.

If desired the hot water outlet pipe 17 leading 30 from the waste heat hot water tank 7 may be provided with a suitable shut off valve to stop the flow of water from the waste heat hot water tank 7 into the main hot water tank 19. The pipe 17 may of course be provided 35 with an extension leading to a hot water faucet provided for the purpose of drawing off hot water from the waste heat hot water supply tank 7 when desired.

For the purpose of supplying cold water 40 to the water tank 7 a cold water supply pipe 42 leads into the bottom of the fixture and is conducted upwardly around the hot water tank 19 and into the flue chamber 40 where the cold water supply coil or pipe is divided 45 so that one branch of the pipe will be conducted through the water circulating lines of the refrigerator to absorb a certain amount of heat from the refrigerator unit before being discharged. The second branch 16a of the water supply pipe 42 leads to the auxiliary water tank 7.

50 The front wall forming the front closure of the flue chamber 40 is provided with an upper opening 43 (Figure 4) adapted to be closed by means of a removable panel or door 44. The upper opening 43 permits convenient access to be had to the refrigerator unit apparatus. Provided in the front wall of the flue chamber 40 below the upper opening 43 is a long lower opening 45 adapted to be closed by a long closure panel or door 46. The lower opening 45 permits convenient access 55 to be had to the piping and other apparatus which is mounted in the lower portion of the flue chamber 40.

60 Mounted in the lower front portion of the cabinet or fixture adjacent the side wall of

the flue chamber is a gas range or stove provided with a plurality of top burners 47 individually controlled by means of a plurality of gas cocks or valves 48. The gas range is provided with an oven 49 adapted to be closed by means of an oven door 50. An oven burner 51 is mounted beneath the oven 49 and in the upper portion of a broiler oven 52 adapted to be closed by a broiler door 53. Rigidly secured to the broiler door 53 is a broiler drawer 54 having a transverse wall or partition 55 rigidly supported near the rear end thereof. Guides or supports 56 are secured to the inner face of the broiler door 53 and to the partition plate 55 to afford a support for the broiler pan 57 as illustrated in Figure 5.

65 Supported on the rear portion of the broiler drawer 54 behind the partition 55 is a removable ash receiving receptacle or pan 58 which forms a part of an incinerator appliance mounted behind the gas range in an incinerator chamber 59. The top 60 of the gas range extends rearwardly over the top of the incinerator chamber 59 and is provided with an opening adapted to be closed by an incinerator cover 61 which when open provides 70 an opening through which garbage can be placed in the incinerator. The incinerator cover 61 is pivotally mounted at 62 upon a head 63 which is rigidly secured on the upper end of a vertical slide rod 64. The cover control rod 64 is slidably mounted in brackets 65 secured on the back of the fixture. Pivotally connected to the lower end of the actuating rod 64 is a link 66 (Figure 9) to the end of which is pivotally connected one 75 end of a fulcrumed lever 67. The lever 67 is fulcrumed intermediate its ends at 68 within a chamber 69 provided in the outer side wall of the gas range. The rear end of the fulcrumed lever 67 projects through a slot 70 provided in the rear wall of the cabinet or fixture. Pivotally connected to the inner end of the lever 67 is the upper end of a connecting link 71 the lower end of which projects through an opening in the bottom of the cabinet or fixture and is pivotally connected to a foot pedal 72 the rear end of which is pivotally supported on a suitable bracket 73 secured to one of the fixture legs 2 as illustrated in Figure 3. The front end of the food pedal 72 projects a slight distance in front of the lower portion of the fixture near one side of the same to permit convenient operation of the control mechanisms governing 80 the opening of the incinerator cover 61.

85 Rigidly secured to the inner faces of the vertical walls forming the incinerator housing 74 are a plurality of angle bar supports 75 to form a shoulder upon which the upper peripheral flange 76 of an incinerator basket is adapted to be removably supported with said basket projecting downwardly within the incinerator housing 74 as clearly illustrated in Figure 6.

The incinerator basket comprises two parallel vertical side walls 77 connected at their upper ends by parallel end walls 78 the lower ends of which connect up with a pair of downwardly converging slanting walls 79 the lower ends of which are spaced a short distance apart and are connected to a small arched bottom wall 80. The inclined or slanting walls 79 of the incinerator basket are provided with longitudinal openings 81. Shiftably mounted adjacent the inner faces of the inclined walls 79 of the incinerator basket are grate plates 82 which are also provided with a plurality of longitudinally disposed slots or openings to permit ashes from the interior of the incinerator to be discharged through the slots 81 of the inclined walls 79 when the grate plates 82 are actuated. Pivots connected to the grate plates 82 are connecting rods 83 which project upwardly and are pivotally connected to the incinerator cover 61. The lower ends of the rods 83 are slotted at 84 (Figure 8) to engage on the projecting ends of rods or shafts 85 which are mounted transversely upon the upper ends of the grate plates 82. The shafts 85 are adapted to project through slots 86 provided in the upper portion of the rear wall 77 of the incinerator basket.

Projecting upwardly through the lower portion of the incinerator housing chamber 59 is a gas pipe 87 on the end of which an elbow 88 is secured to afford a support for a pair of inclined gas feed pipes 89 and 90.

Mounted on the upper end of the auxiliary gas feed pipe 89 is a low flame burner 91 which is adapted to burn continuously in order to provide a means for keeping a consistent drying atmosphere in the incinerator to dry the material within the incinerator basket. A high flame burner 92 (Figure 6) is mounted on the upper end of the fuel or gas pipe 90. It will thus be noted that the incinerator is provided with a dual burner arrangement which eliminates the need of a pilot light. When the incinerator cover is opened the incinerator basket may be removed so that access can easily be had to the dual incinerator burner. The incinerator burner 92 is adapted to be controlled by means of an incinerator burner cock or control valve 93 mounted adjacent an oven control burner cock or valve 94 both of which are mounted on the same common gas line on which the range burner control cocks or valves 48 are mounted. A common lighter 95 (Figure 5) is mounted in a convenient position between the range burners 47 and is controlled by a pilot button 96 which is accessible from the front of the range as clearly illustrated in Figure 1. Mounted in the flue chamber 40 is an incinerator pilot 97 for the incinerator high flame burner 92. Also mounted in the flue chamber 40 adjacent the incinerator pilot 97 is an oven pilot 98. Both the incinerator

pilot 97 and the oven pilot 98 have the upper ends thereof positioned so that they may be lighted from the common lighter 95.

Mounted in the flue chamber 40 below the main outlet flue 3 is an auxiliary flue pipe 99 the upper end of which connects with the outlet chamber 9 of the drum head 6 provided at one end of the waste heat water heater tank 7 as clearly illustrated in Figure 3. Connected with the flue elbow 4 of the main flue 3, is a housing or box 100 having a fan or blower device mounted therein to provide additional draft for removing cooking odors and burned gas from the range oven, the incinerator and from the other gas burning appliances forming a part of the combination fixture. The lower end of the auxiliary flue pipe 99 connects up with an incinerator flue 101, an oven flue box 103 and with a range burner flue box 102 to permit the escape of burned gases and odors from the various appliances into the auxiliary flue pipe 99 to permit escaping heat from the gases to pass through the pipes 12 and 13 of the waste heat water heater before escaping through the main flue 3.

A flue box 104 is also provided to connect the hot water heater drum head 29 with the lower end of the auxiliary flue pipe 99. It will thus be noted that all the various gas fired appliances forming part of the combination gas fixture are arranged to be connected up with the common outlet flue permitting the various burned gases, odors etc. to escape from the fixture passing through the flue pipes forming part of the waste heat water unit to cause the water in the waste heat water tank 7 to be heated by the waste heat thereby making a highly efficient arrangement for not only heating an additional water supply but also affording a considerable saving of gas for the heating of the main hot water tank which consequently may be of reduced size in view of the fact that the waste water heater is provided.

The various appliances are so arranged that access to the operating mechanisms thereof is adapted to be readily had through the various doors and panels provided in the front of the combination gas fixture.

The improved combination fixture provides an outstanding advantage in that it combines a plurality of gas fired appliances in a compact cabinet or housing adapted to occupy a small amount of floor space and furthermore adapted to be had at a material reduction in cost over what the cost would be if a plurality of individual gas burning appliances were purchased. Another advantage of the improved combination gas fixture is found in the convenient arrangement of the various appliances permitting food to be removed from the refrigerator to the gas range in a substantially horizontal plane and furthermore allowing refuse from the food to

be deposited directly into the incinerator basket by opening the incinerator cover 61 through the actuation of the incinerator control foot pedal 72. With the convenient close

5 arrangement of the various gas appliances in the improved gas fixture it will be noted that many steps will be saved for the housewife or a person using the improved fixture.

It will of course be understood that various 10 details of construction may be varied through a wide range without departing from the principles of this invention, and it is therefore not purposed limiting the patent granted hereon otherwise than necessitated by the scope of the appended claims.

I claim as my invention:

1. A combination gas fixture formed as a 20 unitary piece of furniture comprising in combination a gas controlled refrigerator and a gas controlled hot water heater disposed in one side of the fixture, a gas range, a gas controlled incinerator and a waste heat water heater mounted in the opposite side of the fixture, and a common flue device arranged 25 in an intermediate section of the fixture adapted to conduct exhaust gases through the waste heat water heater to cause heating of the water therein.

2. A combination gas fixture formed as 30 a single article of furniture including in combination a gas refrigerator appliance, a gas hot water appliance, a gas range, a gas fired incinerator appliance, a common flue for the gas range and the various appliances 35 to afford an escape for waste gases and heat, and an auxiliary appliance connected in said common flue to utilize the waste heat escaping through the flue.

3. A combination gas fixture of unitary 40 form embracing in combination a gas fired hot water heater, a gas controlled refrigerator unit mounted thereabove, a gas range, a gas fired incinerator behind said gas range, a common flue connected with the refrigerator, 45 the hot water heater, the gas range and the incinerator, and an auxiliary water heater located above the gas range and above the incinerator and connected with the common flue to permit the waste flue gases to pass 50 therethrough to cause the heat in the flue gases to be largely recovered in the water contained in the auxiliary water heater.

4. A combination gas fixture in the form 55 of a unitary piece of furniture comprising in combination a gas controlled refrigerator, a gas controlled main hot water heater mounted therebelow, a utensil compartment mounted below the refrigerator and in front of the main hot water heater, a gas range, a gas fired incinerator mounted behind said range, an auxiliary water heater mounted above the gas range and said incinerator, and a common flue connected with the refrigerator, the main hot water heater, the gas range, and 60 said incinerator and passing through said

auxiliary water heater to permit the water in the auxiliary water heater to be heated by the heat recovered from the flue gases escaping through the common flue.

5. A unitary culinary fixture comprising 70 in combination a gas refrigerator, a main water heater mounted below the rear portion of the refrigerator, a utensil compartment mounted below the front portion of the refrigerator in front of the main water heater, a gas range, a gas incinerator mounted behind the gas range, a foot pedal controlled cover for the incinerator mounted in the top of the gas range, an auxiliary water heater mounted above the incinerator, a hood 75 for the gas range enclosing said auxiliary water heater, and a common waste gas escape flue connected with the refrigerator, the main water heater, the gas range and the incinerator and passing through the auxiliary water heater to permit the waste heat included in the flue gases to be largely recovered in heating the water contained within the auxiliary water heater.

6. A combination culinary fixture embracing 80 in combination a gas controlled refrigerator, a gas fired main water heater, a gas range, a gas fired incinerator behind the gas range, a broiler drawer mounted in the lower portion of the gas range, a broiler pan removably supported on said drawer, an incinerator ash receptacle also mounted on said broiler drawer behind the broiler pan to permit the ash receptacle to be removed when the broiler drawer is pulled out, an auxiliary water heater mounted above the gas range, a common flue passing through the auxiliary water heater and connected with the refrigerator, the main water heater, the gas range and the incinerator to permit the waste gases escaping 95 from said appliances to be utilized in heating the water in said auxiliary water heater.

7. A combination culinary fixture comprising 100 in combination a gas controlled refrigerator, a gas fired main water heater, a gas range, a gas fired incinerator, a hood mounted above the gas range, an auxiliary water heater enclosed by said hood, a pivoted apron forming a part of said hood and adapted 105 to be adjusted to extend further over the gas range, and a common flue connected with the refrigerator, the main water heater, the gas range and said incinerator and connected with said auxiliary water heater to permit the escaping flue gases to be utilized in the auxiliary water heater to heat the water therein.

8. A combination culinary fixture comprising 115 in combination a gas controlled refrigerator, a gas fired main water heater, a gas range, an incinerator housing, a gas fired removable incinerator basket supported in said housing, a foot pedal controlled cover for the incinerator housing, a common flue connected 120

to permit the escape of waste gases from the various appliances and an auxiliary water heater connected to utilize the heat from the waste gases passing through the common flue to heat the water in said auxiliary water heater.

9. A combination gas fixture comprising in combination a plurality of gas fired appliances, a common waste gas escape flue connected with said appliances, an auxiliary appliance adapted to utilize the heat in the escaping flue gases, one of said appliances comprising an incinerator housing, a cover for said housing, manually controlled means for governing the opening of said incinerator cover, a removable incinerator basket in said incinerator housing, and grate members adjustably mounted in said basket and connected with said incinerator cover for operation thereby.

10. A combination gas fixture comprising in combination a plurality of gas controlled appliances including an incinerator housing, a cover pivotally mounted thereon, a foot pedal device connected with the cover to facilitate operation thereof, an incinerator basket removably mounted in said incinerator housing, grate members adjustably mounted in said incinerator basket, and means connected with said grate members and with the incinerator cover to permit operation of the grate members when the cover is operated.

11. A combination gas fixture comprising in combination a plurality of gas controlled appliances including an incinerator comprising an incinerator housing, a cover therefor, a foot pedal mechanism connected with the cover to facilitate operation thereof, a slotted incinerator basket removably mounted in said incinerator housing, grate members mounted in said incinerator basket, means connecting said grate members with the incinerator cover to cause operation of the grate members when the foot lever mechanism is operated, and burner devices mounted in said incinerator housing beneath the removable incinerator basket.

12. A combination fixture of the class described comprising a gas range, a gas incinerator mounted therebehind, a cover for said incinerator mounted in the rear portion of the top of said gas range, a removable incinerator basket in said incinerator, a common flue connected with the gas range and with said incinerator, grate members adjustably mounted in said incinerator basket and connected with said cover, and means for operating said cover to open the same and simultaneously actuate said grate members.

13. A combination fixture of the class described comprising in combination a gas heater, a gas refrigerator mounted thereabove, a gas range mounted to one side of said gas heater, a gas incinerator mounted behind the gas range and accessible through

the top of said stove, and a common flue connected with the gas refrigerator, the gas heater, the gas range and said gas incinerator.

14. A combination fixture of the class described comprising in combination a gas range, a gas incinerator mounted therebehind, a cover for said incinerator mounted in the top of said gas range, a common flue connected with the gas range and with said incinerator, a slide member mounted in the gas range and beneath said incinerator, a broiling device removably supported on the slide member and an ash receptacle for said incinerator also mounted on said slide member and adapted to be positioned beneath the incinerator when the slide member is in place.

15. A combination gas fixture formed as a single article of furniture including in combination a gas refrigerator appliance, a gas hot water appliance, a gas range, a common flue for the gas range and the various appliances to afford an escape for waste gases and heat, and an auxiliary appliance connected in series with said common flue to utilize the waste heat escaping through the flue.

In testimony whereof I have hereunto subscribed my name at Chicago, Cook County, Illinois.
